CLAIM

The ornamental design for a framed kennel door, as shown and described.

DESCRIPTION

FIG. 1 is a perspective view of a framed kennel door, showing my new design within an environment of use;

FIG. 2 is a perspective view of a framed kennel door;

FIG. 3 is a left side view thereof;

FIG. 4 is a bottom plan view thereof;

FIG. 5 is a top plan view thereof;

FIG. 6 is a right side view thereof;

FIG. 7 is a front view thereof; and,

FIG. 8 is a back view thereof.

In FIG. 1, the broken lines depicting a kennel represent environmental subject matter that forms no part of the claimed design.
